UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

ELECTRIC-CURRENT-SUPPLYING MECHANISM.

1,209,310.

Specification of Letters Patent. Patented Dec. 19, 1916.

Original application filed July 14, 1909, Serial No. 507,635. Renewed April 11, 1914, Serial No. 831,342.
Divided and this application filed August 28, 1914. Serial No. 859,095.

To all whom it may concern:

Be it known that I, NILS D. LEVIN, a citizen of the United States, residing at Columbus, in the county of Franklin and State 5 of Ohio, have invented certain new and useful Improvements in Electric-Current-Supplying Mechanisms, of which the following is a specification, reference being had therein to the accompanying drawings.

10 The object of the invention is to provide an electric locomotive having a cable reel mechanism with improved driving and controlling means.

In the accompanying drawings I have 15 shown the embodiment of my invention which I now deem preferable. Various changes may, however, be made if desired.

Of the drawings,—Figure 1 is a side view 20 of a locomotive and cable reeling mechanism embodying my invention. Fig. 2 is a perspective view of a cable reeling apparatus and controlling mechanism therefor, constructed in accordance with my invention. Fig. 3 is another perspective view of the 25 same taken from another point. Fig. 4 is a vertical section of the reel. Fig. 5 is a plain view of the entire reeling apparatus. Fig. 6 is a side elevation. Fig. 7 is an end elevation with the controlling lever removed. Fig. 8 is a view partly in cross section and 30 partly in elevation of the brake mechanism.

A represents more or less diagrammatically a locomotive or other vehicle which, so far as my invention is concerned, can be of 35 any of a number of sorts. An electric locomotive is shown similar to that in the Sessions Patent #821,317 and it is provided with a main frame B, track wheels C, axles D, and electric motors E, connected to the 40 said axles and track wheels.

Numeral 1 designates a base plate which is intended to be secured to suitable parts of an electric locomotive or other moving object to be supplied with electric current by 45 means of the cable. As shown it is mounted upon the main frame B of the locomotive.

The reel 2 is revolvably mounted in a standard 3 which is secured to the base plate 1 and is arranged with its axis in a vertical 50 position, although this, of course, is immaterial to the principle of my invention. The reel may be constructed in any suitable manner, and as shown in the drawings, it con-

sists of the wooden drum 4 and the metallic end plates 5, 5, which serve to retain the 55 cable laterally. The cable may be of the single conductor type or of the double conductor type. In the drawings, except in Fig. 4, I have shown a single conductor cable; and in Fig. 4 I have illustrated a 60 double conductor cable showing how it may be attached to the reel. The cable 6 is wound upon the drum and is shown in Fig. 4 as having contained within it two conductors 6^a and 6^b, the inner end of one of which is 65 electrically connected to the metallic hub 7 of the reel, and thus grounded, and the inner end of the other of which is electrically connected to the collecting ring 8 which engages with the brush 9. From the brush 9 current 70 is led to the motor 17 for driving the reel and to the motors E E for driving the locomotive. In this manner the electric circuit can be completed by the cable to any movable current consuming device which it 75 is impracticable otherwise to electrically connect with a source of electric current.

Suitable guides 10, 10 are provided at opposite points near the reel periphery where 80 by the cable may be furnished an anti-friction support as it leaves the reel, and prevented from being worn against the stationary parts of the mechanism. The oppositely arranged guides 10, 10 make it possible for the cable to be wound onto or un- 85 wound from the reel at either side thereof. The guard plates 11, 11 are mounted upon the base plate 1 in such position that their upper faces are flush with the inner face of the lower reel flange 5, and in close prox- 90 imity to the periphery of this flange. These guards prevent the cable from fouling under the reel.

The rope sheave 12 is rigidly secured to the under side of the reel and is engaged by 95 the endless rope 13 which also passes around the rope sheave 14. This latter sheave 14 is mounted upon a vertical shaft 15 which is supported in bearings carried by the horizontal frame or carrier 16. This frame com- 100 prises arms which are bolted to the frame or casing of the motor 17 for driving the reel. The motor frame is mounted to turn about a vertical pivot pin mounted in a stationary bearing 18. On account of this pivotal 105 mounting the motor frame 17 and the sheave

14 are movable bodily about a vertical axis, and the sheave 14 can be caused to approach or recede from the reel sheave 12.

The sheave 14 is connected to the motor by 5 means of a pinion 19 on the armature shaft of the motor and a bevel gear 20 keyed to the shaft 15 upon which the sheave 14 is also rigidly mounted.

In order to control the movement of the 10 carrier 16 and the motor and other parts connected to it, I provide a pivoted hand lever 22 which can be locked in any one of a plurality of positions by means of a dog 28 which may engage a segmental rack 27. 15 Between the lever 22 and the frame 16 is a link 24. The link 24 is secured at one end to a sleeve 25 which engages the shaft 15. The other end of the link 24 has a yieldable connection through the spring 26 with the 20 hand lever. It will be noted that by adjusting the position of the hand lever the carrier 16 and the sheave 20 may be yieldingly held in any desired position to properly tension the rope belt 13.

25 The reel is braked by means of the block 32 which is pivoted to the base plate at 33, and which engages with the rope receiving groove of the sheave 12 at a point adjacent the sheave 14. The block 32 is caused to 30 bear against the sheave 12 by the plunger 34 which is slidably mounted in the frame 16 extending from the motor. This plunger is held in its outermost position by means of the spring 21 which bears at one end against 35 the collar 35 at the outer end of the plunger, and at the other end against the frame 16. The nut 36 prevents the plunger from being entirely removed from its support in the frame 16. When the motor and the frame 16 40 rigidly secured thereto are swung about the pivot 18 and toward the reel, the plunger 34 engages the brake block 32 which is thereby yieldingly forced against the sheave 12.

Upon the box 29 are mounted one or more 45 stationary contacts 30. A movable contact 31 is mounted upon the outer end of the carrier 16 and is adapted to engage with the stationary contacts 30 as the motor casing and frame 16 are swung about the vertical 50 pivot at 18. The contacts 30 are arranged on the arc of a circle about the axis of the pivotal connection of the motor casing with the bed plate so that the movable contact 31 may properly register with each of them. 55 When several contacts 30 are provided as shown in Fig. 5, they are suitably electrically connected together except the one at the left marked 30^a which is an idle contact insulated from all other parts. It will be 60 readily understood that by moving the lever 22 away from the reel, electrical connection will be established through the motor to start it, and the rope belt 13 will be simultaneously tightened. The apparatus is so 65 adjusted that the motor acquires consider-

able velocity before the rope becomes tight enough to drive the reel. When by means of the lever 28, the current is shut off and the grip of the rope 13 is loosened, the brake 32 is simultaneously applied, and by means of the same lever, when the current is turned on and the rope clutch thrown into operation, the brake is simultaneously released.

It will be understood that the rope driving means which I have provided serves as a simple, efficient and cheap friction device for transmitting a rotative force to the reel.

In operation it is desirable that the cable be maintained at a substantially uniform tension during winding, and in order that 80 this may be done the drive sheave 14 may be operated at a speed somewhat in excess of that corresponding to the speed of travel of the vehicle or locomotive. When this is done, the tendency is for the reel to rotate 85 at a speed somewhat greater than is permitted by the cable. As a result, it is necessary for slippage to take place, and this occurs between the rope and one or both of the sheaves. It will be seen that the cable tension must at all times be in proportion to the 90 resistance to slippage offered at the sheaves; and this resistance can be varied by adjusting the tension in the rope in the manner before described.

It will be understood that it is not necessary to disconnect and stop the motor every time the locomotive is moved in the cable unwinding direction. As a matter of fact, it is possible and in fact preferable, especially when the distance of unwinding is short, to permit the motor to operate continuously. As stated above a slippage will take place between the rope and the sheaves as the reel is controlled by the cable tension. The continuously acting motor serves to transmit a continuous winding torque to the reel and this torque is present irrespective of the direction of rotation. In other words the motor is so connected that it tends to 110 turn the reel in the winding direction even though the reel be forced by the cable to turn in the unwinding direction. This construction is of considerable importance as it positively insures a proper tension in the 115 cable at all times. The motorman can devote his entire attention to the handling of the locomotive, the starting, stopping and reversing of it, the attachment of cars, etc., and the reel motor in the mean time will 120 keep the cable taut, winding it when the locomotive moves in one direction and permitting it to unwind under predetermined tension when the locomotive moves in the other direction.

Obviously, many changes can be made in the details of the construction, as, for instance, in the mounting of the reel, in the form of the power means for driving the sheave 14, in the means for tightening the 130

rope, in the means for applying the brake, etc. I have herein used the word "rope" in referring to the connection between the two sheaves but it will be understood that any 5 suitable endless friction element can be used without departing from the spirit of the invention. Changes in these and other respects are not considered to be departures from the invention as set forth in the following 10 claims.

This application constitutes a division of my application, Serial Number 507,635, filed July 14, 1909, renewed April 11, 1914, as Serial Number 831,342, and issued April 30, 15 1915, as Patent No. 1,136,246.

What I claim is:—

1. The combination with a vehicle adapted to travel forward and backward and having an electric driving motor, of an electric conductor cable adapted to be connected at its free end to a fixed electric conductor and serving to supply current to the motor during the said forward and backward movement, a reel for winding the cable during 20 movement in one direction and unwinding it during movement in the other direction, the speed of rotation of the reel in both directions being entirely controlled by the cable, a rope sheave connected with the reel to rotate therewith, a power driving means for the reel, a drive sheave connected with the power means, and an endless rope permanently 25 engaging the said sheaves, the said rope serving in combination with the sheaves to provide a friction drive for the reel whereby its speed of rotation can be controlled by the cable irrespective of the speed of the power means.

2. The combination with a vehicle adapted to travel forward and backward and having an electric driving motor, of an electric conductor cable adapted to be connected at its free end to a fixed electric conductor and serving to supply current to the motor during 40 the said forward and backward movements, a reel for winding the cable during movement in one direction, and unwinding it during movement in the other direction, the speed of rotation of the reel in both directions being entirely controlled by the cable, a rope sheave connected with the reel to rotate therewith, a power driving means for the reel, a drive sheave connected with the power means, an endless rope permanently 45 engaging the said sheaves, the said rope serving in combination with the sheaves to provide a friction drive for the reel whereby its speed of rotation can be controlled by the cable irrespective of the speed of the power means, and manually controllable means for regulating the tension in the rope.

3. The combination with a vehicle adapted to travel forward and backward and having an electric driving motor, of an electric

conductor cable adapted to be connected at its free end to a fixed electric conductor and serving to supply current to the motor during the said forward and backward movement, a reel for winding the cable during the 70 movement in one direction and unwinding it during movement in the other direction, the speed of rotation of the reel in both directions being entirely controlled by the cable, a rope sheave connected with the reel to 75 rotate therewith, a power driving means for the reel, a drive sheave connected with the power means, an endless rope permanently engaging the said sheaves, the said rope serving in combination with the sheaves to 80 provide a friction drive for the reel whereby its speed of rotation can be controlled by the cable irrespective of the speed of the power means, and manually controllable means for moving the drive sheave bodily 85 to change the tension in the rope.

4. The combination with a vehicle adapted to travel forward and backward and having an electric driving motor, of an electric conductor cable adapted to be connected at 90 its free end to a fixed electric conductor and serving to supply current to the motor during the said forward and backward movements, a reel for winding the cable during movement in one direction and unwinding it 95 during movement in the other direction, the speed of rotation of the reel in both directions being entirely controlled by the cable, a rope sheave connected with the reel to rotate therewith, a power driving means for the reel, a drive sheave connected with the power means, an endless rope permanently 100 engaging the said sheaves, the said rope serving in combination with the sheaves to provide a friction drive for the reel whereby 105 its speed of rotation can be controlled by the cable irrespective of the speed of the power means, and a manually controllable brake supplemental to the rope for resisting the rotation of the reel in the unwinding direction.

5. The combination with a vehicle adapted to travel forward and backward and having an electric driving motor, of an electric conductor cable for supplying current to 115 the motor during the said forward and backward movement, a reel for winding the cable during movement in one direction and unwinding it during movement in the other direction, a rope sheave connected with the reel to rotate therewith, a power driving means for the reel, a drive sheave connected with the power means, an endless rope permanently 120 engaging the said sheaves, the said rope serving in combination with the sheaves to provide a friction drive for the reel whereby its speed of rotation can be controlled by the cable tension irrespective of the speed of the power means, a brake supplemental to the rope for resisting the 125 rotation.

tion of the reel in the unwinding direction, and means for simultaneously decreasing the tension in the rope and applying the said brake.

5 6. The combination with a vehicle adapted to travel forward and backward and having an electric driving motor, of an electric conductor cable adapted to be connected at its free end to a fixed electric conductor and 10 serving to supply current to the motor during the said forward and backward movement, a reel for winding the cable during movement in one direction and unwinding it during movement in the other direction, 15 the speed of rotation of the reel in both directions being entirely controlled by the cable, a rope sheave connected with the reel to rotate therewith, a second electric motor for driving the reel, the said second motor 20 being operable independently of the first said motor and receiving its current from the said cable, a drive sheave connected with the said second motor, and an endless rope permanently engaging the said sheaves, the 25 said rope serving in combination with the sheaves to provide a friction drive for the reel whereby its speed of rotation can be controlled by the cable irrespective of the speed of the second motor.

30 7. The combination with a vehicle adapted to travel forward and backward and having an electric driving motor, of an electric conductor cable adapted to be connected at its free end to a fixed electric conductor and 35 serving to supply current to the motor during the said forward and backward movement, a reel for winding the cable during movement in one direction and unwinding it during movement in the other direction, the 40 speed of rotation of the reel in both directions being entirely controlled by the cable, a second electric motor operable independently of the first said motor and receiving its current from the said cable, a frictional 45 power connection between the second motor and the reel, whereby the motor can transmit a constant winding torque to the reel irrespective of its direction or speed of rotation under the control of the cable, and manually 50 controllable means operable while the second motor is in operation for removing the pressure between the elements of the friction connection thereby interrupting the transmission of the said torque.

55 8. The combination with a vehicle adapted to travel forward and backward and having an electric driving motor, of an electric conductor cable adapted to be connected at its free end to a fixed electric conductor and 60 serving to supply current to the motor during the said forward and backward movement, a reel for winding the cable during movement in one direction and unwinding it during movement in the other direction, the 65 speed of rotation of the reel in both direc-

tions being entirely controlled by the cable, a rope sheave connected with the reel to rotate therewith, a second electric motor for driving the reel, the said second motor being operable independently of the first said 70 motor and receiving its current from the said cable, a drive sheave connected with the said second motor, an endless rope permanently engaging the said sheaves, whereby the motor can transmit a constant winding torque to the reel irrespective of its direction or speed of rotation under the control of the cable, and manually controllable means for loosening the said rope thereby 75 interrupting the transmission of the said 80 torque.

9. The combination with a forward and backward moving vehicle having an electric driving motor, of an electric conductor cable for supplying current to the motor during 85 the said forward and backward movement, a reel for winding the cable during movement in one direction and unwinding it during movement in the other direction, a second electric motor operable independently 90 of the first said motor and receiving its current from the said cable, a power connection between the second motor and the reel, a brake independent of the said power connection for resisting the rotation of the reel, 95 means for opening and closing the circuit of the second motor, means for applying and releasing the said brake, and a manually controllable lever operable irrespective of the direction of rotation of the reel to simultaneously 100 operate the last two said means to stop the motor and apply the brake or start the motor and release the brake.

10. The combination with a forward and backward moving vehicle having an electric 105 driving motor, of an electric conductor cable for supplying current to the motor during the said forward and backward movement, a reel for winding the cable during movement in one direction and unwinding it 110 during movement in the other direction, a second electric motor operable independently of the first said motor and receiving its current from the said cable, a normally operative power connection between the second motor and the reel, a brake independent of the said power connection for resisting the rotation of the reel, means for breaking the 115 said power connection, means for applying and releasing the said brake, and a manually controllable lever operable irrespective of the direction of rotation of the reel for simultaneously 120 operating the last two said means to apply the brake and interrupt the transmission of power or to release the brake 125 and cause the transmission of power.

11. The combination with a forward and backward moving vehicle having an electric driving motor, of an electric conductor cable for supplying current to the motor during 130

- the said forward and backward movement, a reel for winding the cable during movement in one direction and unwinding it during movement in the other direction, a second electric motor operable independently of the first said motor and receiving its current from the said cable, a normally operative power connection between the second motor and the reel, a brake independent of the said power connection for resisting the rotation of the reel, means for opening and closing the circuit of the second motor, means for breaking the said power connection, means for applying and releasing the said brake, and a manually controllable lever, operable irrespective of the direction of rotation of the reel, for simultaneously operating the last three said means to stop the motor, break the power connection and apply the brake or start the motor, complete the power connection and release the brake.
12. The combination with a vehicle adapted to travel forward and backward and having an electric driving motor, of an electric conductor cable for supplying current to the motor during the said forward and backward movement, a reel for winding the cable during movement in one direction and unwinding it during movement in the other direction, a rope sheave connected with the reel to rotate therewith, a power mechanism for driving the reel, a drive sheave connected with the said power mechanism, an endless rope permanently engaging the said sheaves, the said rope serving in combination with the sheaves to provide a friction drive for the reel whereby its speed of rotation can be controlled by the cable tension irrespective of the speed of the second motor, means for tightening and loosening the said endless rope, a brake for resisting the rotation of the
- 5 13. The combination with a vehicle adapted to travel forward and backward and having an electric driving motor, of an electric conductor cable for supplying current to the motor during the said forward and backward movement, a reel for winding the cable during movement in one direction and unwinding it during movement in the other direction, a rope sheave connected with the reel to rotate therewith, a second electric motor for driving the reel, the said second motor being operable independently of the first said motor and receiving its current from the said cable, a drive sheave connected with the said second motor, an endless rope 10 permanently engaging the said sheaves, the said rope serving in combination with the sheaves to provide a friction drive for the reel whereby its speed of rotation can be controlled by the cable tension irrespective of the speed of the second motor, means for tightening and loosening the said endless rope, means for opening and closing the circuit of the electric motor, a brake for resisting the rotation of the reel, and a manually controllable lever for simultaneously loosening the rope opening the motor circuit and applying brake or for simultaneously tightening the rope closing the motor circuit and releasing the brake.
